HINGE

Richard B. Poillman, Detroit, Mich.

Application January 3, 1947, Serial No. 719,951

5 Claims.

(Cl. 16—164)

1

This invention relates to hinges for closures and in particular to concealed hinges.

One object of this invention is to provide a hinge which is concealed within the closure and closure frame respectively yet which permits the closure to be swung from its closed position to an arc of 180 degrees or more so that the closure will swing into a position flat against the wall or even partially around the corner.

Another object is to provide a concealed closure hinge which will permit the use of a closure with a cover flange to cover and conceal the crack between the closure and the closure frame, yet which will permit the closure to be swung outward into an open position while causing the flange to completely clear the closure frame or wall without danger of colliding therewith.

Another object is to provide a concealed closure hinge, as set forth in the preceding objects, wherein the closure is connected to the closure frame or wall by links mounted on fixed pivots, thereby eliminating the necessity for pivots sliding in grooves or guides and the consequent wear and noise during opening, and the rattling in the wind, due to the resulting loose connection.

Another object is to provide a concealed closure hinge which is adaptable for use not only on doors and door frames but also for cabinets, chests or other devices where it is desirable to conceal the hinge completely.

Other objects and advantages of the invention will become apparent during the course of the following description of the accompanying drawings, wherein:

Figure 1 is a horizontal section through a closure having a concealed closure hinge according to a preferred form of the invention, taken along the line 1—1 in Figure 2, with the hinge and closure in their closed positions;

Figure 2 is a vertical section through the structure shown in Figure 1, taken along the line 2—2 in Figure 1;

Figure 3 is a side elevation partly in section along the line 3—3 in Figure 2, showing the connections of the hinge links to the closure frame;

Figure 4 is a side elevation partly in section along the line 4—4 in Figure 2, showing the connections of the hinge links to the closure;

Figure 5 is a view similar to Figure 1, but showing the closure swung 180° into a fully open position; and

Figure 6 is a diagrammatic view of the hinge structure shown in Figures 1 to 4 inclusive, but

2

with the closure in the fully open position shown in Figure 5.

Referring to the drawings in detail, Figure 1 shows a portion of a wall or closure frame 10, such as a door frame, having a closure opening 11 in which is mounted a closure 12, such as a door. The closure 12 and frame or wall 10 are interconnected by a concealed hinge, generally designated 13, containing the linkage herein-after described. In order to provide a proper clearance and prevent jamming by reason of warping or the like, the closure 12 is spaced away from the closure frame or wall 10 so as to leave a gap or crack 14 between the opposing edge walls 15 and 16 of the closure wall and closure respectively. The front wall 17 of the closure 12 is provided with an overhanging edge portion or edge flange 18 covering and concealing the crack 14 and substantially in engagement with the front surface 19 of the wall or frame 10. The flange 18 thus serves as a cover for the crack 14. While only one hinge 13 is shown in the drawings, it will be understood that at least two such hinges will be employed in the usual installation. All of these are of similar construction and, in the case of extremely long doors or other closures, three or more of the hinges 13 may be employed in order to give the desired strength.

The wall or frame 10 is recessed as at 20 with a cavity of irregular shape to receive a hinge casting 21 having a face plate 22 secured by fasteners 23 to the edge wall 15 of the frame 10. The casting 21 is provided with upper, intermediate and lower walls 24, 25 and 26 respectively interconnected by vertical walls 27 and 28 (Figures 1 and 2). The upper and intermediate walls 24 and 25 are provided with vertically aligned bores 29 and 30 in which is mounted a pivot pin 31. Similarly, the intermediate and lower walls 25 and 26 are provided with vertically aligned bores 32 and 33 for receiving a pivot pin 34. Pivotally mounted upon the pivot pins 31 and 34 and separated from the adjacent walls by washers 35 are upper and lower links 36 and 37 respectively, these links being approximately U-shaped. The links 36 and 37 swing around their pivot pins 31 and 34 in recesses 38 and 39 respectively. The recesses 38 and 39 are open at their sides adjacent the face plate 22 and extend inwardly therefrom (Figures 1 and 2). The links 36 and 37 are secured in any suitable way to the pivot pins 31 and 34, as by pins 40 and 41 respectively.

The outer ends of the U-shaped links 36 and 37 are pivotally mounted on upper and lower pivot pins 42 and 43 respectively and secured thereto by pins 44 and 45. The upper pivot pin 42 is mounted in vertically aligned bores 46 and 47 in the upper and intermediate walls 48 and 49 of a casing 50 having a lower wall 51. The lower pivot pin 43 is similarly mounted in vertically aligned bores 52 and 53 in the intermediate and lower walls 49 and 51 of the casing 50 (Figure 2). The walls 48, 49 and 51 are interconnected by a vertical wall 54 of approximately L-shaped cross-section and are connected to an L-shaped face plate 55 secured to the closure 12 by fasteners 56. Washers 57 are provided between the pivot pins 42 and 43 and their adjacent walls similar to the washers 35 and for the similar purpose of insuring free swinging of the U-shaped links 36 and 37. The walls 48, 49, 51 and 54 serve as the boundaries of upper and lower recesses 59 and 60 of approximately L-shaped cross-section through which the outer ends of the links 36 and 37 swing during the opening and closing motion of the closure 12.

The face plate 55 to which the walls 48, 49, 51 and 54 are connected has rear and side portions 61 and 62 (Figures 1 and 4) arranged respectively at right angles to one another and extending around the corner of the closure 12. The forward edges of the face plate 22 and the face plate portions 62 are engaged by the cover flange 18 which, as previously stated, spans the gap or crack 14 between them so as to conceal the latter.

Operation

The mechanical principle underlying the operation of the hinge 13 of this invention is illustrated diagrammatically in Figure 6 with the initial positions of the pivots 34, 43 and 31, 42 shown at the top of the figure and the subsequent positions of the closure pivots 43 and 42 designated 43' and 42' and shown in the lower part of the figure, the closure 12 in its open position being shown as swung around until it is substantially parallel with the front surface 19 of the wall or frame 10 so that the closure 12 has been swung through an angle of approximately 180°.

The pivots 34, 31, 42 and 43 are positioned so that when the closure 12 is in its open position (Figure 6), a line joining the pivots 42' and 43' will be parallel to a line joining the pivots 42 and 43 in the closed position of the door or closure 12. Under these conditions, the line 42'-43', when extended, will pass through the axis of the pivot 34 (Figure 6). The axis of the pivot 31 is not necessarily located on a straight line between the axes of the pivots 34 and 42, as shown in Figure 6, in order to fulfill this condition, but it may be located to one side or another of the line 34-42 so long as the line 42'-43' is parallel to the line 42-43 and the distances 31-42 and 31-42' remain equal, as they must since the line 31-42 is a radius.

In order that the cover flange 18 shall clear the wall front surface 19 and not dig into it or collide with it, the radius 31-42 of the upper link 36 must be shorter than the radius 34-43 of the lower link. More accurately speaking, it is necessary that the rearwardly located door pivot 43 be on a greater radius of swing 34-43 than the forwardly located pivot 42, for the flange 18 to clear the surface 19 properly. The longer link 37 may obviously be placed above the shorter link 36 instead of below it, as shown in Figures 2, 3 and 4 while still providing a hinge which

operates according to the principles of the invention.

In accordance with these principles, when the door or closure 12 is swung from its closed position (Figure 1) into its fully open position shown in Figure 5 and diagrammatically in Figure 6, the U-shaped links 36 and 37 swing through their respective cavities 38, 39, 59 and 60 into the open, as shown in Figure 5, and the edge flange or cover flange 18 moves away from the front surface 19 of the wall or frame 10. If proper clearance is provided, as when the hinge 13 is mounted in a stanchion at the corner of a compartment, the closure 12 may be swung through an angle even greater than 180 degrees by properly cutting away the respective casings 21 and 50. It is usually found sufficient, however, to open the door or closure 12 into a position parallel with its original closed position. When the door is in a closed position, however, it is completely flush with the opening 11 and fully conceals the same, including the crack or gap 14. Maps, paintings, or other artistic or useful objects larger than the opening 11 may be mounted on the wall surface 19 over the closure 12 so as to conceal the opening 11 since there are no hinge projections which might reveal the presence of the opening 11 beneath the map, painting or other such object. Wall paper may also be mounted on the front wall 17 of the closure 12, and made to match with wall paper similarly mounted on the front wall surface 19 of the wall or frame 10. In this way, the concealed hinge of the present invention substantially forms a secret panel yet is instantly capable of being opened and closed in the manner described above.

While I have shown and described my invention in detail, it is to be understood that the same is to be limited only by the appended claims, for many changes may be made without departing from the spirit and scope of my invention.

What I claim is:

1. A concealed hinge for a closure for a wall opening comprising a wall hinge support having two spaced wall pivots stationarily mounted thereon, a closure hinge support having two spaced closure pivots stationarily mounted thereon, and a pair of links, each of said links pivotally interconnecting one of said wall pivots and one of said closure pivots, one of said closure pivots being positioned to swing on a longer radius from its corresponding wall pivot than the other closure pivot, said closure pivots being aligned with one of said wall pivots when said closure is swung into an open position parallel with its closed position.

2. A concealed hinge for a closure for a wall opening comprising a wall hinge support having two spaced wall pivots stationarily mounted thereon, a closure hinge support having two spaced closure pivots stationarily mounted thereon, and a pair of links, each of said links pivotally interconnecting one of said wall pivots and one of said closure pivots, one of said closure pivots being positioned more remote from its corresponding wall pivot than the other closure pivot from the other's corresponding wall pivot and likewise positioned nearer the rear of the closure than said other closure pivot so as to swing on a longer radius from its corresponding wall pivot than the other closure pivot, said wall hinge support having a pair of recesses of different depths from said opening, said wall pivot linked to said closure pivot of longer swinging radius being mounted in the deeper recess and said wall

pivot linked to said closure pivot of shorter swing-radius being mounted in the shallower recess.

3. A concealed hinge for a closure for a wall opening comprising a wall hinge support having two spaced wall pivots stationarily mounted thereon, a closure hinge support having two spaced closure pivots stationarily mounted thereon, and a pair of links, each of said links pivotally interconnecting one of said wall pivots and one of said closure pivots, one of said closure pivots being positioned to swing on a longer radius from its corresponding wall pivot than the other closure pivot, at least three of said pivots lying in a common plane parallel to the front of said closure in the closed position of said closure.

4. A concealed hinge for a closure for a wall opening comprising a wall hinge support having two spaced wall pivots stationarily mounted thereon, a closure hinge support having two spaced closure pivots stationarily mounted thereon, and a pair of links, each of said links pivotally interconnecting one of said wall pivots and one of said closure pivots, one of said closure pivots being positioned to swing on a longer radius from its corresponding wall pivot than the other closure pivot, at least three of said pivots lying in a common plane in the closed position of said closure and the fourth pivot being positioned rearwardly of said common plane.

5. A concealed hinge for a closure for a wall opening comprising a wall hinge support having two wall pivots positioned at different distances

from said opening along a line approximately co-directional with the front of said wall, a closure hinge support having two closure pivots positioned at different distances from the front of said closure, and a pair of bent links, one of said links pivotally connecting the wall pivot more remote from said opening with the closure pivot more remote from the front of said closure and the other of said links pivotally connecting the wall pivot nearer said opening with the closure pivot nearer the front of said closure, a straight line through said closure pivots passing through the wall pivot more remote from said opening when said closure is swung into an open position parallel with its closed position.
